UNITED STATES PATENT OFFICE.

JAMES D. FRARY, OF NEW BRITAIN, CONNECTICUT, ASSIGNOR TO
LANDERS, FRARY & CLARK, OF SAME PLACE.

DESIGN FOR A LABEL.

Specification forming part of Design No. 7,516, dated June 30, 1874; application filed June 17, 1874.
[Term of Patent 14 years.]

CASE A.

To all whom it may concern:

Be it known that I, JAMES D. FRARY, of New Britain, in the county of Hartford and State of Connecticut, have invented a new Design for a Label; and I do hereby declare the following, when taken in connection with the accompanying illustration, to be a full, clear, and exact description of the same, and which said illustration constitutes part of this specification, and represents one of the labels.

This invention relates to a design for label to be placed upon a package or case of table-cutlery; and consists in the peculiar form of ornamented border, as hereinafter described, and shown in the accompanying illustration, which incloses the descriptive portion of the label and illustrations; also, in the arrangement of the filling in, as shown and described.

The outline of the border is a rectangle, the lower angles filled with a circular ornament inclosing a star, and from the intersection of the circle with the border on the side and bottom, a branch extends inward. A short distance above, a bar of serpentine form extends from one side to the other, forming a panel

at the bottom of the label. The intersection of the bar with the sides is ornamented by scroll-work. The upper angles of the label are filled by a brace of scroll-work. Above this is a panel, within which the number, quantity, or other similar marks are placed. This panel, however, is not essential to the design.

The letter-press is arranged as follows: The make or quality in a segment at the top over a vignette; beneath "Table Cutlery," in a straight line; immediately over the lower panel the manufacturer's name in serpentine line. These three lines, with a vignette of some character, constitute the principal features in the arrangement of the letter-press.

The lower panel is designed to receive an illustration of the manufactory.

I claim as my invention—

The design for label, as shown in the accompanying illustration, and herein described.

JAS. D. FRARY.
